COMBINATION CIGARETTE CONTAINER, LIGHTER, AND DISPENSER

Filed May 8, 1941

UNITED STATES PATENT OFFICE

2,342,748

COMBINATION CIGARETTE CONTAINER,
LIGHTER, AND DISPENSER

Richard Mayer, New Rochelle, N. Y., assignor, by
mesne assignments, to Adolph H. Rosenberg
and Leah S. Rosenberg, both of Clayton, Mo.,
and Samuel M. Rosenberg, University City, Mo.

Application May 8, 1941, Serial No. 392,474

15 Claims. (Cl. 155—86)

This invention relates generally to cigarette containers. More particularly, my invention relates to a certain new and useful improvement in combination cigarette containers, lighters, and dispensers especially, though not exclusively, adapted for automobile use, and has for its chief object the provision of a structure of the type and for the purpose stated which may be readily constructed, which is compact and artistic in form and appearance, which may be easily installed upon the automobile, which may be readily filled, which is easily and conveniently operable for lighting and dispensing the cigarettes successively one by one, which is economical and entirely safe in electrical consumption, and which is efficient and satisfactory in the performance of its intended functions.

And with the above and other objects in view, my invention resides in the novel features of form, construction, arrangement, and combination of parts presently described and pointed out in the claims.

In the accompanying drawing:

Figure 1 is a reduced perspective view of an installed combination cigarette container, lighter, and dispenser constructed in accordance with and embodying my present invention;

Figure 2 is a vertical sectional view of the structure taken approximately on the line 2—2, Figure 1, the dispensing member or tray being in retracted, normal, or housed position;

Figure 3 is a fragmental view similar to Figure 2, the dispensing tray, however, being in swingably projected position for delivery of a lighted cigarette;

Figure 4 is an inverted plan view of the structure;

Figure 5 is an enlarged fragmental front elevational view of the structure with the dispensing tray in projected position as in Figure 3; and

Figure 6 is a sectional view of the structure on approximately the line 6—6, Figure 2.

Referring now more in detail and by reference characters to the drawing, which illustrates a preferred embodiment of the invention, the structure includes a shell or housing A uniquely constructed for installation in and upon the instrument-board B of an automobile. To such end, the shell or housing A includes a top wall 1, a rear wall 2, a bottom wall 3 projecting obliquely downwardly and forwardly from the rear wall 2, and opposite parallel side walls 4, 4', permanently joining said top, bottom, and rear walls and correspondingly sloping along their lower margin, all as best seen in Figures 1, 2, and 3.

the shell top wall 1 and side walls 4, 4', being laterally and outwardly flanged along their front margins, as at 5, for flatwise abutment and securing against the rear face of the board B, as seen in Figure 2.

At a suitable location intermediate the top wall 1 and bottom wall 3, the side walls 4, 4', are suitably formed or provided with registering ways 6, 6, for slidably supporting an ash-drawer or receptacle A', the board B being, of course, suitably apertured for accommodating the drawer A' and the latter having a suitable knob or finger-grip 7 for conveniently enabling use thereof.

The ways 6, 6, thus, as it may be said, divide 15 the shell A into an upper or ash-drawer compartment a and a lower or cigarette-containing compartment a', within which latter the cigarettes C to be lighted and dispensed are conveniently housed, as seen in Figure 2.

As also best seen in Figures 2 and 3, the shell oblique bottom wall 3 is cut away along its forward margin to provide a mouth or discharge-opening, as at 8, having a width slightly greater than the diametral dimension of a standard cigarette C, and approximately at and below the plane of the discharge-opening 8, the board B, which, in effect, forms the front wall of the shell-compartment a', is cut away in the provision of an opening 9 for purposes presently appearing, the opening 9 being normally covered and closed by a spring-pulled flap or door 10 hinged, as at 11, upon the board B and provided with a suitable preferably knob-actuable latch 12 for engagement with the board B for releasably securing the door 10 in normal closed position or in the position thereof best seen in Figures 1 and 2.

T designates the dispensing tray of the structure, which includes an arcuate main or body portion t and hanger-arms t', the latter being pivotally attached, as at 13, to the shell side walls 4, 4', and so located and the parts being so relatively proportioned as to swingably dispose the tray-portion t normally rearwardly of the board B and under the shell A as best seen in Figure 2, 40 and as to swingably project the tray-portion t forwardly and partially through the opening 9 into dispensing position, as best seen in Figure 3. Suitably engaging the pivots 13, the shell side flanges 5, and the hanger-arms t', as best seen in Figure 2, are suitable resilient or spring members 14 for urging the tray T into projected or dispensing position, the door 10 being yieldably swung into, and locked by the latch 12 in, lowered or closure position when the tray T is, and for yieldingly or releasably retaining the same, in

normal position, as also best seen in Figure 2, against the tension of the springs 14.

In turn, the forward marginal part of the tray-portion *t* is centrally cut away, as at 15, and rounded or arcuated in the provision of registering curved fingers 16, 16', for seating or gripping a particular cigarette C being dispensed, the fingers 16, 16', being normally located under and closing the mouth or opening 8 and the space 15 between the fingers 16, enabling convenient removal of such particular cigarette C' when the tray T is in dispensing position, as shown.

Adjacent the bottom wall 3, the shell side walls 4, 4', are provided with closed-end registering slots 17, 17, which are of suitable length and parallel the wall 3 for slidably accommodating tongues 18 oppositely projecting from a plate P disposed within the shell-compartment a' for movement over and relatively to the shell bottom wall 3. The tongues 18 are suitably elongated to also work in suitable enlarged openings 19 in the hanger-arms *t*', so that, under the engagement of the tongues 18 with the shell A at the slots 17 and with the arms *t*' at the openings 19, the plate P, when the tray T is in normal position, will be disposed rearwardly over the shell bottom wall 3 for both agitating the contained cigarettes C and opening the mouth 8 to permit a single housed cigarette C to roll into and upon the fingers 16, 16', and when the tray T is in projected or dispensing position, will be shifted forwardly and closurewise over the mouth 8 for again agitating the contained cigarettes C and co-operation with the bottom wall 3 in supporting the remaining cigarettes C within the shell-compartment a'.

Forming part of tray T, is a side-arm 20, adjacent which the one finger 16' is cut away to provide a space, as at 21. Disposed in such space 21 and presented toward the finger 16', is an electric element E forming part of the lighting means of the structure, the element E being suitably fixed on, but insulated from, the arm 20 and having one side suitably grounded on the automobile. Electrically connected with the other side of the element E, is a conductor 22 having a rearwardly presented yielding extension 23 adapted, when the tray T is in projected, dispensing position, for slidable circuit-closing contact with an arcuate lateral extension 24 of a conducting arm 25 fixed, as at 26, to and upon, and insulated from, the shell A and included by means of a conductor 27 in the circuit, it being, of course, understood that, when the tray T is in normal position, the contact-member 23 will be out of engagement with the arm 25, the circuit will be open, and the element E de-energized.

At the opposite side of the tray T, the finger 16 is cut away in its outer end-portion, as at 28, for providing a working-opening or space for the forwardly presented free or yielding end-portion 29 of a spring presser-strip S fixed at its other end, as at 30, to and upon a second or opposite tray-arm 20' and bent upon itself intermediate its opposite end-positions 29, 30, to include an obliquely disposed cam-portion or section 31, as best seen in Figure 4, for co-operative engagement with a stud 32 fixed upon and projecting from the shell bottom wall 3. It is to be observed that normally, that is to say, when the tray T is in normal retracted position, the strip S will at its cam-portion 31 so engage the stud 32 that its free end-portion 29 will be yieldingly shifted outwardly toward the tray-arm 20'. However, when the tray T is oscillatorily swung to pro-

ject or dispensing position, the strip S will at its cam-portion 31 so engage the stud 32 that its end-portion 29 is free to yieldingly move toward the finger 16 for engaging upon the adjacent end of the particular cigarette C' presented in the fingers 16, 16', for pressing the same at its other end into lighting engagement with the now energized element E.

Accordingly, in use, the shell compartment a' being suitably filled with cigarettes C, the door 10 being latched in closed position, tray T being in normal position, and mouth 8 being open, a single cigarette, designated C', will roll through mouth 8 into, and be supported by, the fingers 16, 16'.

Door 10 being opened, tray T, under the tension of springs 14, oscillates forwardly for projecting the fingers 16, 16', into dispensing position or into the position thereof best seen in Figure 3, when the particular cigarette C' may be readily gripped and removed for consumption.

In such forward oscillation of tray T, the contact-member 23 engages with conducting arm 24, thereby closing the circuit and energizing the element E. At the same time, the strip S is cam-wise shifted with respect to the stud 32 and its free end-portion 29 thereby permitted to shift inwardly for engaging an end of the deposited cigarette C' for pressing the same into lighting engagement at its opposite end with the now energized element E. At the same time, further, the plate P is shifted forwardly into closurewise position over the discharge opening or mouth 8.

The so presented and lighted cigarette C' being removed, door 10 is swingably actuated to closure position and in such movement engages with and shifts the tray T rearwardly to normal position, in which latter position it is retained by again latching the door 10 in closure position. In such returning movement of the tray T, the circuit to the element E is again broken, as described, the free end-portion 29 of the pressure strip S is shifted outwardly under engagement of its cam-portion 31 with stud 32, and the plate P is shifted rearwardly for again opening mouth 8, so that a second cigarette C may freely roll into and upon the fingers 16, 16'.

Thus the housed or contained cigarettes C may be successively removed and dispensed one by one from the shell or container A. The structure efficiently fulfills in every respect the objects stated, and it is to be understood that changes and modifications in the form, construction, arrangement, and combination of the several parts of the structure may be made and substituted for those herein shown and described without departing from the nature and principle of my invention.

Having thus described my invention, what I claim and desire to secure by Letters Patent is:

1. A cigarette container and dispenser comprising a shell for housing the cigarettes to be dispensed, the shell having a bottom wall provided with a discharge opening and an apertured front wall, in combination with means including a yieldingly oscillatory tray swingable through the aperture in the shell front wall for removing the housed cigarettes successively one by one from the shell, and a closure for said aperture for releasably securing the tray in normal position for receiving a cigarette discharging through said opening.

2. A cigarette container and dispenser comprising, in combination, a shell for housing the cigarettes to be dispensed, the shell having a fixed

bottom wall provided with a discharge opening and an apertured front wall, a tray having a main portion having cigarette-supporting fingers and hanger arms, the latter being pivotally attached to the shell for swingably disposing said fingers normally under said opening for receiving from said bottom wall a discharging cigarette and for projecting said fingers forwardly through said apertured front wall for dispensing said cigarette, and means including a member shiftable over said bottom wall for closing said discharge opening when the tray fingers are in dispensing position.

3. A cigarette container and dispenser comprising, in combination, a shell for housing the cigarettes to be dispensed, the shell having a fixed bottom wall provided with a discharge opening and an apertured front wall, a tray having a main portion having cigarette-supporting fingers and hanger arms, the latter being pivotally attached to the shell for swingably disposing said fingers normally under said opening for receiving from said bottom wall a discharging cigarette and for projecting said fingers forwardly through said apertured front wall for dispensing said cigarette, springs engaging the tray and shell for yieldingly oscillating the tray into dispensing position, and means including a member shiftable over said bottom wall for closing said discharge opening when the tray fingers are in dispensing position.

4. A cigarette container and dispenser comprising, in combination, a shell for housing the cigarettes to be dispensed, the shell having a fixed bottom wall provided with a discharge opening and an apertured front wall, and means for removing the housed cigarettes successively one by one from the shell, said means including a tray having a main portion having cigarette-supporting fingers and hanger arms, the latter being pivotally attached to the shell for swingably disposing said fingers normally in retracted position under said opening for receiving from said bottom wall a discharging cigarette and for projecting said fingers forwardly through said apertured front wall for dispensing said cigarette, springs engaging the tray and shell for yieldingly oscillating the tray into dispensing position, and means for releasably retaining the tray in normal retracted position.

5. A cigarette container and dispenser comprising, in combination, a shell for housing the cigarettes to be dispensed, the shell having a bottom wall provided with a discharge opening and an apertured front wall, means for removing the housed cigarettes successively one by one from the shell, said means including a tray having a main portion having cigarette-supporting fingers and hanger arms, the latter being pivotally attached to the shell for swingably disposing said fingers normally under said opening for receiving a discharging cigarette and for projecting said fingers forwardly through said apertured front wall for dispensing said cigarette, and springs engaging the tray and shell for yieldingly oscillating the tray into dispensing position, and means for releasably retaining the tray in normal position, said last means including a door hinged upon said front wall for closure of said aperture.

6. A cigarette container and dispenser comprising, in combination, a shell for housing the cigarettes to be dispensed, the shell having a fixed downwardly sloping bottom wall provided with a cigarette discharge opening, and means for removing the housed cigarettes successively

one by one from the shell, said means including a tray having cigarette-supporting fingers normally disposed under said opening for receiving a cigarette discharging therethrough from said bottom wall and oscillatorily disposed away from said opening for dispensing said cigarettes, and a shiftable plate having connection with the tray for disposition over said opening for closure thereof when the tray-fingers are in dispensing position.

7. A cigarette container and dispenser comprising a shell for housing the cigarettes to be dispensed, the shell comprising a bottom wall having a discharge opening and side walls having closed end slots in parallelism with the bottom wall, in combination with means for removing the housed cigarettes successively one by one from the shell, said means including a tray having fingers normally disposed under said opening for receiving a cigarette discharging therethrough and oscillatorily disposed away from said opening for dispensing said cigarette, and means for closing said opening when the fingers are in dispensing position, said last means including a slide plate shiftable within the shell and having tongues working in said slots and having engagement with the tray.

8. A cigarette container and dispenser comprising a shell for housing the cigarettes to be dispensed, the shell comprising a bottom wall having a discharge opening and side walls having closed end slots in parallelism with the bottom wall, in combination with means for removing the housed cigarettes successively one by one from the shell, said means including a tray having cigarette-supporting fingers and hanger arms, the latter having registering openings and being pivotally attached to the shell and the fingers being normally disposed under said opening for receiving a cigarette discharging therethrough and oscillatorily disposed away from said opening for dispensing said cigarette, and means for closing said opening when the fingers are in dispensing position, said last means including a slide plate shiftable within the shell and having tongues working in the slots of the shell side walls and in the openings of said arms.

9. A cigarette container and dispenser comprising, in combination, a shell for housing the cigarettes to be dispensed, the shell having a discharge opening, means for removing the housed cigarettes successively one by one from the shell, said means including a tray having cigarette-supporting fingers normally disposed under said opening for receiving a cigarette discharging therethrough and oscillatorily disposed away from said opening for dispensing said cigarette, a normally de-energized cigarette-lighting element carried by the tray, and means for energizing said element when the fingers are in dispensing position for lighting the cigarette being dispensed.

10. A cigarette container and dispenser comprising, in combination, a shell for housing the cigarettes to be dispensed, the shell having a discharge opening, means for removing the housed cigarettes successively one by one from the shell, said means including a tray having cigarette-supporting fingers normally disposed under said opening for receiving a cigarette discharging therethrough and oscillatorily disposed away from said opening for dispensing said cigarette, a normally de-energized cigarette-lighting element carried by the tray, and means for energizing said element when the fingers are in dispensing position for lighting the cigarette being dispensed,

said last means including a contact-member on the tray adapted for connection with a source of current, the element having grounded connection on one side with said source and a contact-member on the tray electrically engageable with the first contact-member and element when the tray is in dispensing position.

11. A cigarette container and dispenser comprising, in combination, a shell for housing the cigarettes to be dispensed, the shell having a discharge opening, means for removing the housed cigarettes successively one by one from the shell, said means including a tray having cigarette-supporting fingers normally disposed under said opening for receiving a cigarette discharging therethrough and oscillatorily disposed away from said opening for dispensing said cigarette, a normally de-energized cigarette-lighting element carried by the tray, means for energizing said element when the fingers are in dispensing position for lighting the cigarette being dispensed, and means including a spring strip for endwise successively yieldingly engaging the dispensed cigarettes with the lighting element.

12. A cigarette container and dispenser comprising, in combination, a shell for housing the cigarettes to be dispensed, the shell including spaced side walls, a front wall having an aperture, and a fixed cigarette-supporting bottom wall having a discharge opening, means for removing the housed cigarettes successively one by one from the shell, said means including an oscillatory tray having cigarette-supporting fingers swingable under said opening for receiving from said bottom wall the discharging cigarettes and for dispensing the cigarettes forwardly through said apertured front wall, and means including an element carried by, and swingable with, the tray for lighting the cigarettes as they are successively dispensed.

13. A cigarette container and dispenser comprising, in combination, a shell for housing the cigarettes to be dispensed, the shell including spaced side walls, a front wall having an aperture, and a fixed cigarette-supporting bottom wall having a discharge opening, means for removing the housed cigarettes successively one by one from the shell, said means including an oscillatory tray having cigarette-supporting fingers swingable under said opening for receiving from said bottom wall the discharging cigarettes and for

dispensing the cigarettes forwardly through said apertured front wall, means including an element carried by, and swingable with, the tray for lighting the cigarettes as they are successively dispensed, and means for endwise successively engaging the finger-supported cigarettes with the lighting element.

14. A cigarette container and dispenser comprising, in combination, a shell for housing the cigarettes to be dispensed, the shell including spaced side walls, a front wall having an aperture, and a fixed cigarette-supporting bottom wall having a discharge opening, means for removing the housed cigarettes successively one by one from the shell, said means including an oscillatory tray having cigarette-supporting fingers swingable under said opening for receiving from said bottom wall the discharging cigarettes and for dispensing the cigarettes forwardly through said apertured front wall, means including an element carried by, and swingable with, the tray for lighting the cigarettes as they are successively dispensed, means for endwise successively engaging the finger-supported cigarettes with the lighting element, said last means including a spring strip also carried by, and swingable with, the tray and having a cam-portion, and a stud fixed upon the shell bottom wall engaging the cam-portion of the strip during oscillatory movements of the tray.

15. A cigarette container and dispenser comprising, in combination, a shell for housing the cigarettes to be dispensed, the shell including spaced side walls, a front wall having an aperture, and a fixed cigarette-supporting bottom wall sloping downwardly toward the front wall and at its front margin being spaced from the upper edge of said aperture in the provision of a cigarette discharge opening, means including a yieldingly swingable tray having projecting fingers and hanger arms, the arms being pivoted to the side walls of the shell for movement of the fingers under said discharge opening for successively receiving the cigarettes from said bottom wall and dispensing the same forwardly through said aperture, and a plate adjustably shiftable over said bottom wall by and with said hanger arms for closing said discharge opening when the tray is in cigarette-dispensing position.

RICHARD MAYER.
